UNITED STATES PATENT OFFICE.

EGBERT H. GOLD, OF CHICAGO, ILLINOIS.

HEATING SYSTEM FOR REFRIGERATOR-CARS AND THE LIKE.

1,242,898.

Specification of Letters Patent. Patented Oct. 9, 1917.

Application filed November 5, 1913. Serial No. 799,364.

To all whom it may concern:

Be it known that I, EGBERT H. GOLD, a citizen of the United States, residing at Chicago, in the county of Cook and State 5 of Illinois, have invented certain new and useful Improvements in Heating Systems for Refrigerator-Cars and the like, of which the following is a specification.

My invention relates to the heating of 10 railway cars, particularly by steam, and the primary object of the invention is to provide a suitable equipment for supplying heat, as occasion may require, to railway cars such, for example, as refrigerator cars which ordinarily do not require heating but which it 15 is desirable to heat during certain periods and in certain seasons when certain kinds of freight, such, for example, as fruit or vegetables are transported.

It is customary to use refrigerator cars 20 for the transportation of fruit, vegetables, and like perishable commodities in certain seasons or in travel through certain parts of the country without having such cars 25 iced. When such commodities are subjected in transit to comparatively low temperatures not only is icing unnecessary but it is desirable to heat the cars in order to avoid the danger of freezing; although possibly 30 only for a part of the journey as, for example, when fruit is transported from a tropical or semi-tropical climate to more northerly regions. However, this heating of refrigerator cars, desirable as it is under 35 some circumstances, has not ordinarily been done, in the first place, because of the cost involved in equipping such cars with the heating systems of the type customarily used on railroad cars, which is very high con- 40 sidering the comparative infrequency of the occasions demanding the heating of cars of this sort, and, in the second place, because of the space which the heating coils of such systems occupy in the car, the permanent 45 installation of heating coils in the car decreasing the carrying capacity of the car without serving any useful function during the larger part of the time during which the car is in service. The employment of 50 stoves in this connection is objectionable as stoves require frequent fueling and constant attention and, moreover, are likely to set fire to the train in case of accident.

My invention provides a very satisfactory 55 heating equipment for cars of this type consisting, first, of steam heating or radiating

devices, one or more for each car, which are mounted within the car but so that they may be readily removed therefrom at such times as the car does not need to be heated; second, 60 a system of steam pipes provided, preferably with regulating devices, which is permanently installed on the car, preferably underneath the same, and is adapted to convey steam from the locomotive boiler, or other 65 common source of supply of steam common to the several cars of the train, and deliver the same preferably in automatically regulated quantities to the heating element or elements when the same are in operative 70 position, and, third, an air circulatory system within the car, preferably also a permanent installation, with which the heating elements coöperate to produce a uniform or relatively uniform distribution of heat 75 through the entire car. The air circulatory feature of my invention is not perhaps absolutely essential but is, nevertheless, a highly desirable feature of the invention. With an equipment of this sort the cost of heating 80 refrigerator cars, and the like, is sufficiently reduced and the space in the car sacrificed to this purpose is minimized to such an extent that it is entirely feasible, 85 practical and economical to heat such cars whenever temperature conditions and the character of the cargo may require it. For example, if a railway owns a thousand refrigeration cars the chances are that only a small proportion of these cars at any time 90 will be used under conditions making heating desirable. If it were necessary to equip all of these cars with the ordinary heating systems the cost of installation might be wholly out of proportion to the benefits received, to say nothing of the diminution in carrying capacity resulting from having steam coils permanently installed in each of 95 said cars. By utilizing my invention a railroad company can equip each of its refrigeration cars with a train pipe, regulating devices and such piping as may be necessary to supply the heaters with steam from the train pipe and carry off the water of condensation, and in addition to this equipment 100 it may have on hand just enough of the removable radiating elements of my invention—ordinarily a comparatively small number will do—to meet the requirements for heating such cars at such times and for such 105 periods as they may need to be heated. These heating elements, moreover, may be 110

distributed at different points on the road as the traffic demands.

The invention is illustrated, in a preferred embodiment, in the accompanying drawings, 5 wherein—

Figure 1 is a vertical longitudinal sectional view of a refrigerator car, the section being taken on line 1—1 of Fig. 2;

Fig. 2, a sectional plan view of the car; 10 Fig. 3, a vertical sectional view showing the construction of the radiating element and of the fitting in the car floor in which it is mounted;

Fig. 4, a view in elevation, with parts in 15 section, of a portion of the permanently installed supply pipe system showing a preferred form of regulating device operated to supply steam to the radiator at atmospheric pressure;

20 Fig. 5, a sectional view of the fitting in which the heating element when used is mounted but shown as closed up with a plug as is intended when the heating element is removed, the section being taken on line 25 5—5 of Fig. 6;

Fig. 6, a plan view of the parts shown in Fig. 5;

Fig. 7, a plan view of the upper end of 30 the radiating element showing the means employed for supporting this end of said element;

Fig. 8, a sectional plan taken on line 8—8 of Fig. 3;

Fig. 9, a plan view of the lower casting 35 or member of the radiating element, and

Figs. 10 and 11 sectional plans on lines 10—10 and 11—11 respectively, of Fig. 3.

Like characters of reference designate like parts in the several figures of the drawings.

40 Referring to the drawings, 25 designates a refrigerator car of ordinary construction provided at opposite ends with the icing chambers 26. The car is permanently equipped with a steam train pipe 27 which 45 may be provided at opposite ends with the usual coupling means (not shown) for coupling it with the train pipes of the adjacent cars of a train. The car is also provided with a fitting 28 with which the radiating element is designed to have an interlocking engagement, this fitting being preferably 50 fixed in the flooring 29 of the car and formed with an inlet port 30 adapted to receive steam from the train pipe 27 through a supply pipe 31, 31^a, and a discharge port 32 connected by a pipe 33 with the thermostat chamber of a vapor regulator 34 which is 55 interposed between sections 31 and 31^a of the supply pipe and operates to maintain steam in the radiating element when the latter is in operative position at atmospheric pressure.

The radiating element is composed preferably of a lower member or casting 35 formed 60 with a steam duct 36, air intakes 37 and air

ducts 38, an upper member 39 formed with a steam duct 40 and air ducts 41, a plurality of circumferentially arranged steam pipes 42 and central pipe 42^a preferably wound with wires 43, 43^a to increase their radiating 70 capacity, which pipes are interposed between the upper and lower members connecting their steam ducts, and a sheathing 44, preferably of sheet metal, which surrounds the pipes 42. The lower casting 35 75 is formed with an interior cylindrical web 45 divided by a web 46 into an inlet chamber 47 communicating by port 48 with the inlet port 30 of the fitting 28, and an outlet chamber 49 having a port 50 adapted to register 80 with the outlet duct 32 of the fitting. The upper end of the outlet chamber 49 communicates with the duct 36 by a port 51.

The centrally arranged radiating pipe 42^a connects the inlet chamber 47 through ducts 85 52 with the steam duct 40 of the upper casting above referred to. The course of the medium through the steam passages of the radiating element is shown by the unfeathered arrows in Fig. 3; that is, the steam from pipe 31^a passes through port 30 of the fitting 28 and port 48 of the radiating element into chamber 47 and thence through pipe 42^a and ducts 52 into the duct 40 of the upper casting 39, then down through 90 the radiating pipes 42 into the duct 36 in the lower casting 35 and from there through duct 51 into the outlet chamber 49 and through ports 50 and 32 of the lower casting 35 and fitting 28, respectively, into the 100 outlet pipe 33. The projecting portion of the cylindrical web 45 of the lower casting is formed with a lug 53 which enters a vertical slot 54 in the fitting 28 when the heating element is thrust into the fitting, this 105 slot communicating with a horizontal arculate slot 55 into which the lug is moved by giving the heating element a quarter turn. By turning the heating element in this manner it is interlocked with the fitting and the discharge port 50 is brought into register with port 32 of the fitting.

The upper end of the radiating element is preferably supported by an arm 56 pivoted to a bracket 57 attached to the side 115 wall 58 of the car, the extremity of said arm being formed with a slot 59 so that it will fit over a lug 60 formed on the top of the upper casting 39. The lug 60 is perforated to receive a locking pin 61 attached 120 by a chain 62 to the arm 56. When the heating device is removed from the car the arm is fastened against the wall of the car (as shown in the dotted lines in Fig. 3) by means of a lug 63 formed on bracket 57 125 and perforated to receive the locking pin 61. The arm is slotted at 64 so that it will fit down over lug 63.

Preferably the car is furnished with an air circulatory system which co-operates with 130

the heating device above described for effecting a distribution of the heat throughout the car; this apparatus consisting, in the preferred form of the invention shown, of an air pipe or trunk 65 arranged in the upper part of the car and preferably extending from end to end of the same and certain arrangements for connecting the air passages of the heating device with such trunk. As shown, the trunk is provided with an intake pipe consisting of a fixed section 66 and a telescoping section 67. The latter is adapted to fit over the upper end of the heating device and is slotted at 68 for the arm 56. The feathered arrows, Figs. 1 and 3, show the course of the air currents through the heater and car.

As stated, the permanently installed supply system for supplying the heating device with steam preferably includes a vapor regulator, designated 34, for maintaining the steam in the heater and in the ducts leading thereto at substantially atmospheric pressure. There is a distinct advantage in utilizing atmospheric pressure steam in connection with the apparatus above described because with steam at a pressure little if any in excess of that of the atmosphere, the connection between the heating element and the fitting in which it is mounted does not have to be a steam-tight connection. If steam were introduced into the heating device at train pipe pressure there would be necessarily considerable leakage unless the joint between the heating element and the fitting were steam packed. It would be difficult to maintain a properly packed joint between two elements which have to be separated and put together at frequent intervals. Any leakage of steam, however small, into a car loaded with fruit or vegetables would be undesirable.

The vapor regulator 34 is a common type of device, and consists of a valve casing 69, a thermostat casing 70, a valve 71, and a thermostat 72 which operates the valve 71 through the instrumentality of rods 73, 74 and bell crank 75; the valve 71 controlling a port 76 between the inlet chamber 77 to which pipe 31 leads, and an outlet chamber 78 from which steam passes to the radiating element through pipe 31^a. The thermostat 72 is expanded by steam discharged from the heating element through pipe 33 so that it shuts off or throttles the supply to the heating element before the pressure in said element is materially above atmospheric pressure.

By reference to Fig. 2 it will be seen that, according to the preferred embodiment of my invention, the car is provided with two sets of apparatus such as that above described. Both may be and preferably are identical in their construction. If desired, one set of apparatus might be omitted and

appropriate changes made in the air circulatory system if need be for producing an equal distribution of the hot air through the car.

When the car does not require heating the steam is shut off by closing a valve 79 in pipe 31 and the heating element is removed by first lifting the telescopic section 67 of the air trunk intake and disconnecting the upper end of the heating device from the supporting arm 56, and then turning the heating device back so that it may be lifted out of the fitting 28. Preferably a plug 80 is provided which fills the cavity in the fitting 28 and is provided with a duct 81 which puts the stem supply pipe section 31^a into communication with the discharge pipe 33 so that there will be no leakage of steam into the car in case valve 79 should be inefficient or should be opened or left opened by accident. Preferably the supply pipe section 31 is provided with a branch 82 fitted with a valve 83 and a coupler member 84, the latter being adapted to be engaged by the coupler of the steam supply pipe used for heating cars while standing in stations. By this arrangement the car may be heated, if necessary, when uncoupled from the train.

As will be obvious, other modifications might be made without departing from the principles of my invention. Therefore I do not wish to be understood as limiting the invention to the particular constructions, arrangements and devices shown and described except so far as such limitation is explicitly made in certain of the claims herein; my purpose being to claim all the patentable novelty of my invention both broadly and narrowly.

I claim:

1. The combination with a railway car, of a steam supply system permanently installed on the outside of the car comprising a fitting formed with a socket below the floor level and accessible from the interior of the car, a radiator having a member adapted to have an interlocking engagement with said fitting whereby the radiator is supplied with steam from said supply system when set up in the car and which permits the radiator to be removed from the car at will, and a plug to close said socket and to lie below the floor level when the radiator is removed.

2. The combination with a railway car, of a steam supply system permanently installed on the car below the floor level comprising a fitting located in the floor of the car and accessible from the interior thereof, an air distributing pipe permanently installed in the upper part of the car, and a radiator having a steam circuit and an air passageway, said radiator being adapted to be disengageably connected with said fitting and said air distributing pipe so that the

- 4
- steam circuit of the radiator is put into communication with the supply system and the air passageway thereof with said air distributing pipe.
5. The combination with a railway car, of a fitting in the floor of the car, a steam supply pipe leading to said fitting, an air trunk extending through the upper part of the car, and a radiating element provided 10 with a steam conduit adapted to communicate with said supply pipe through said fitting and with an air passageway opening into the car at the bottom, said trunk being provided with an intake pipe which comprises 15 a movable section adapted to fit over the upper end of said radiating element so as to direct air from the air passageway therein into said trunk.
6. The combination with a railway car, 20 of a fitting in the floor of the car, a steam supply pipe leading to said fitting, an air trunk extending through the upper part of the car, and a radiating element provided with a steam conduit adapted to communicate 25 with said supply pipe through said fitting and with an air passageway opening into the car at the bottom, said trunk being provided with an intake pipe which comprises a fixed section and a telescoping section, the latter adapted to fit over the upper 30 end of said radiating element so as to direct air from the air passageway therein into said trunk.
7. The combination with a railway car, 35 of supply and discharge pipes, a fitting secured to the car provided with supply and discharge ports with which said supply and discharge pipes communicate respectively, and a radiating element provided with a member adapted to have an interlocking engagement with said fitting and provided 40 with a steam conduit communicating at opposite ends with the ports of said fitting respectively, and a plug adapted to be put into said fitting, when the radiating element is 45 removed, having a duct which is adapted to place the supply port of the fitting in communication with the discharge port.
8. The combination with a railway car, 50 of supply and discharge pipes, a fitting secured to the car provided with supply and discharge ports with which said supply and discharge pipes communicate respectively, and a radiating element provided with a member adapted to engage with said fitting 55 and provided with a steam conduit communicating at opposite ends with the ports of said fitting respectively, and a plug adapted to be put into said fitting, when the 60 radiating element is removed, having a duct which is adapted to place the supply port of the fitting in communication with the discharge port.
9. The combination with a railway car, 65 of an air trunk for distributing hot air throughout the car, a steam supply pipe permanently installed in said car, a radiating element having a steam space therein and an air passageway therethrough adapted to be removably mounted in the car so 70 that the steam space therein communicates with the supply pipe, and means for connecting the radiating element to the air trunk which establishes communication between the air passageway in the radiating 75 element and said trunk.
10. The combination with a railway car, of an air trunk for distributing hot air throughout the car with an intake pipe comprising a telescoping section, a steam supply 80 pipe permanently installed in said car, a radiating element having a steam space therein and an air passageway extending therethrough adapted to be removably mounted in the car so that the steam space 85 therein communicates with the supply pipe, said telescoping section being adapted to fit over the end of the radiating element so as to put the air passageway therein in communication with said trunk.
11. The combination with a railway car, 90 of an air trunk for distributing hot air throughout the car and provided with an intake pipe comprising a telescoping section, a steam supply pipe permanently installed in said car, a heating element having a steam space therein and an air passageway extending through the same, said heating 95 element being removably mounted in said car so that the steam space therein communicates with the supply pipe, and a supporting device for supporting the upper end of said heating element, said telescoping section of the air trunk intake pipe being 100 formed so that it fits over the upper end of 105 said radiating element and its supporting device.
12. The combination with a railway car, of an air trunk for distributing hot air throughout the car and provided with an intake pipe comprising a telescoping section, a steam supply pipe permanently installed in said car, a heating element having a steam space therein and an air passageway 110 extending through the same, said heating element being removably mounted in said car so that the steam space therein communicates with the supply pipe, and a supporting member pivoted to the wall of the car and adapted to be locked to the upper end of 115 said heating element, the telescoping section of the air trunk intake pipe being 120 formed so as to fit over said supporting member and the upper end of said heating element.
13. The combination with a railway car provided with supply and discharge pipes and a fitting in the floor of the car with which said pipes communicate, and a radiating element comprising a lower member, 125

an upper member, each provided with a steam duct and an air passageway, steam pipes connecting the steam ducts of said members, and a casing surrounding said pipes; said lower member being formed so as to have an interlocking relation with said fitting.

12. The combination with a railway car provided with supply and discharge pipes and a fitting in the floor of the car with which said pipes communicate, and a radiating element comprising a lower member, an upper member, each provided with a steam duct and an air passageway, steam pipes connecting the steam ducts of said members, and a casing surrounding said pipes; said lower member being formed so as to have an interlocking relation with said fitting, and means for supporting the upper end of said radiating element.

13. The combination with a railway car provided with supply and discharge pipes and a fitting in the floor of the car with which said pipes communicate, and a radiating element comprising a lower member, an upper member, each provided with a steam duct and an air passageway, steam pipes connecting the steam ducts of said members, and a casing surrounding said pipes; said lower member being formed so as to have an interlocking relation with said fitting, and means for supporting the upper end of said radiating element comprising an arm pivoted to the side of the car and adapted to be secured to said upper member.

14. The combination with a railway car provided with supply and discharge pipes and a fitting in the floor of the car with which said pipes communicate, a radiating element comprising a lower member, an upper member, each provided with a steam duct and an air passageway, steam pipes connecting the steam ducts of said members, and a casing surrounding said pipes; said lower member being formed so as to have an interlocking relation with said fitting, and an air trunk adapted to receive the air from the air passageway of said radiating element.

15. In a temporary heating system for railway cars, the combination with a supply system consisting of a steam supply conduit permanently installed on the car, of a socket fitting arranged flush with the floor level of the car, having a supply pipe connected with said conduit and provided with a discharge pipe for the water of condensation, and a radiator arranged within the car having an interlocking connection with said socket fitting whereby, when interlocked therewith, it receives steam from said supply pipe and discharge its water of condensation through

said discharge pipe, and whereby said radiator may be readily disconnected from said fitting and removed from the car at will. 65

16. In a temporary heating system for railway cars, the combination with a steam supply conduit permanently installed on the car, of a fitting permanently connected with said conduit and having its upper surface substantially flush with the floor level, and a removable and portable radiator adapted to have an interlocking connection with said fitting so as to be supplied with steam from the supply conduit through said fitting. 75

17. In a temporary heating system for railway cars, the combination with a steam supply conduit permanently installed on the car, of a fitting in the car connected with said conduit, an air distributing system permanently installed in the car, and a radiator adapted to be detachably connected with said fitting and with said air distributing system to receive steam from the former and deliver heated air to the latter. 80

18. In a temporary heating system for railway cars, the combination with a steam supply conduit thereon below the floor level, of an air-distributing duct in the upper portion of the car and a portable radiating element adapted to be detachably interposed between and operatively connected with the steam supply and the said air duct so as to receive steam from the former and deliver heated air to the latter. 95

19. The combination with a railway refrigerator car having icing compartments at opposite ends thereof opening into the interior of the car at the top and bottom; of a steam supply system permanently installed on the car below the floor line; an air conduit near the top of the car the ends of which are open and extend adjacent said compartments; and a radiator adapted to be detachably connected with said supply system and air conduit to receive steam from the former and deliver heated air to the latter. 100

20. In a temporary heating system for a railway box car having a side door, the combination with a steam supply conduit permanently installed on the car, of a fitting connected with said conduit and located in the car near one of the side doors thereof, an air distributing pipe extending lengthwise of the car with its ends open, and a radiator 110 adapted to be detachably connected with said fitting and with said air distributing pipe to receive steam from the former and deliver heated air to the latter. 115
